UNITED STATES PATENT OFFICE.

MICHAEL B. BOWEN, OF DECATUR, ILLINOIS, ASSIGNOR TO FARIES MANUFACTURING COMPANY, OF DECATUR, ILLINOIS, A CORPORATION OF ILLINOIS.

DESIGN FOR A LIGHTING FIXTURE.

Application filed January 25, 1923. Serial No. 4,983. Term of patent 7 years.

To all whom it may concern:

Be it known that I, MICHAEL B. BOWEN, a citizen of the United States, and residing at Decatur, in the county of Macon and State of Illinois, have invented a new, original, and ornamental Design for Lighting Fixture, of which the following is a specification, reference being had to the accompanying drawing, forming part thereof.

The figure is a perspective view of a lighting fixture showing my new design.

I claim:

The ornamental design for a lighting fixture, as shown.

MICHAEL B. BOWEN.
